(57) **CLAIM**

The ornamental design for a mug, as shown and described.

DESCRIPTION

FIG. 1 is a front elevational view of a mug according to the present design;

FIG. 2 is a first side elevational view thereof;

FIG. 3 is a back elevational view thereof;

FIG. 4 is a second side elevational view thereof;

FIG. 5 is a top view thereof;

FIG. 6 is a bottom view thereof;

FIG. 7 is a front elevational view of an alternative embodiment mug according to the present design;

FIG. 8 is a first side elevational view thereof;

FIG. 9 is a back elevational view thereof;

FIG. 10 is a second side elevational view thereof;

FIG. 11 is a top view thereof; and,

FIG. 12 is a bottom view thereof.

The surface shading represents color contrast.
